Primary Examiner — Darlington Ly*Assistant Examiner* — Daniel J Domino(74) *Attorney, Agent, or Firm* — Morgan, Lewis & Bockius LLP(57) **CLAIM**

The ornamental design for a display screen with graphical user interface, as shown and described.

DESCRIPTION

FIG. 1 is a front view of a display screen with graphical user interface;

FIG. 2 is a view of a second embodiment thereof;

FIG. 3 is a third embodiment thereof;

FIG. 4 is a view of a fourth embodiment thereof;

FIG. 5 is a fifth embodiment thereof;

FIG. 6 is a view of a sixth embodiment thereof;

FIG. 7 is a view of a seventh embodiment thereof;

FIG. 8 is a view of an eighth embodiment thereof;

FIG. 9 is a view of a ninth embodiment thereof; and,

FIG. 10 is a view of a tenth embodiment thereof.

The broken lines showing a display screen and elements of the graphical user interface, as well as the elements with chain-like breaks illustrate portions of the article. No subject matter depicted in broken lines or chain-like breaks form part of the claimed design.
